Application June 16, 1938, Serial No. 213,956

8 Claims. (Cl. 2—169)

This invention relates to gloves and particularly to improvements in the thumb constructions of gloves.

Substantially all types of dress gloves are provided with thumb portions which are formed separately and are sewed into apertures in the palm, or palm and back portions of the glove. This type of construction forms a well fitting thumb but is somewhat unsightly and also lacks flexibility. 5 for the reason that the seam which connects the thumb to the body of the glove extends across the palm around the base of the thumb muscle and upwardly across the back portion of the glove. The seam, in effect, constitutes a reinforcement which resists easy bending of the thumb and likewise produces a zone of weakness in the glove.

Numerous attempts have been made to do away with the seam connecting the thumb piece to the glove and many glove constructions have been made in which the seam is eliminated. However, none of these constructions has been satisfactory for the reason that the resulting gloves do not fit properly and as a consequence are useful only 20 as work gloves. Usually the integral thumb portions are formed symmetrically on the back and palm portions of the glove and as a consequence project outwardly from the glove in the plane thereof so that the glove can be worn with equal 25 facility on either hand and properly fits neither hand.

An object of the present invention is to provide properly fitting gloves having no seam on the palm portion thereof.

Another object of the invention is to provide gloves in which the major portion of the thumb thereof is formed integrally with the palm and/or back portion, whereby seams extending across the palm and/or back of the glove adjacent the 30 base of the thumb are avoided.

Other objects of the invention will become apparent from a description of typical forms of gloves embodying the present invention.

A typical form of glove comprises a palm portion and a back portion, each having corresponding finger portions which are connected by at least one fourchette which extends along the sides of the finger portions over the ends thereof to maintain the finger portions in spaced relationship throughout and a thumb portion which is formed integrally with the palm and/or back of the glove. The thumb portion is non-symmetrically disposed with respect to the palm and back portions and when in completed form is disposed 40 in the proper position to receive a thumb, that is

normally tends to project forwardly from the palm portion of the glove rather than in the plane of the palm and back portions. The thumb portion forms the major portion of the thumb of the glove and the thumb is completed by means 5 of a fourchette having a generally oval shaped end which is connected to the edges of the thumb portion. The fourchette extends from the tip of the thumb downwardly into the crotch between the thumb and forefinger and may extend along 10 the outer portion of the forefinger over the end and down into the crotch between the fore and second fingers as disclosed in my copending applications Serial No. 193,226 filed March 1, 1938, and Serial No. 204,552 filed April 27, 1938. These 15 copending applications disclose various forms of fourchettes for connecting the finger portions of the gloves and also forming the inner portion of a thumb for the glove. The fourchettes disclosed in these applications may be continuous strips 20 which extend from the bottom of the inclined crotches between the fingers over the ends and down into the next crotch, or they may be formed of several pieces joined in suitable manner to produce the effect of a fourchette which maintains the finger portions on the back and palm of 25 the glove in spaced relationship throughout. Any of these types of fourchettes may be used with equal facility for connecting the finger portions of the gloves embodying the present invention. 30

The thumb portion of the gloves embodying the present invention may be formed as an integral part of the palm and back portions of the gloves, and in this form of the invention the original blank has the thumb portion disposed between the 35 back and palm portions and inclined at different angles relatively to the longitudinal axis of the finger portions thereof, whereby the thumb portion is unsymmetrically disposed and is located in the proper position to receive the thumb of 40 the human hand.

Gloves of the type including seamless palms and/or backs are extremely flexible because there is no seam to bind and resist movement of the thumb. They, likewise, have an extremely novel 45 appearance. For example, the palm portion and the back of the thumb portion may be produced from one type or color or leather, while the back portion of the glove may be formed from another type or color of material. Likewise the fourchettes which connect the finger portion and form the inner portion of the thumb may be of 50 contrasting materials or colors, thereby producing a highly ornamental effect. The integral thumb construction greatly strengthens the 55

gloves by eliminating seams which may rip because of the stresses to which they are subjected, and also facilitates the manufacture of such gloves for the reason that the amount of sewing required to assemble the gloves is greatly reduced.

For a better understanding of the invention reference may be had to the accompanying drawings, in which:

Figure 1 is a plan view of the palm blank for a typical form of glove embodying the invention;

Figure 2 is a plan view of the back blank of the glove;

Figure 3 is a plan view of a typical form of fourchette for connecting the finger portions of the glove;

Figure 4 is a plan view of a fourchette for connecting adjacent edges of the little finger, the palm and back of the glove;

Figure 5 is a plan view of a fourchette for completing the thumb portion and connecting the outer and inner edges of the forefinger portions of the glove;

Figure 6 is a perspective view of the glove formed from the blanks shown in Figures 1 to 5, inclusive, looking in the direction of the palm of the glove;

Figure 7 is a perspective view of the glove shown in Figure 6 looking in the direction of the back of the glove;

Figures 8 and 9 are plan views of the back and palm portions of a modified form of glove;

Figure 10 is a perspective view of the glove formed from the blanks shown in Figures 8 and 9;

Figure 11 is a plan view of a modified form of blank in which the palm, back and thumb portions of the glove are formed integrally;

Figure 12 is a perspective view of the glove formed from the blank disclosed in Figure 11;

Figure 13 is a plan view of another form of blank in which the palm, back and thumb portions are formed integrally;

Figure 14 is a perspective view of the form of glove produced from the blank shown in Figure 13;

Figure 15 is a plan view of palm and back blanks for a modified form of glove in which the thumb portion is integral with the back blank; and

Figure 16 is a perspective view of the glove produced from the blanks shown in Figure 15.

The form of glove disclosed in Figures 6 and 7 is formed from a palm portion 10 having finger portions 11, 12, 13 and 14 formed thereon and a back portion 15 having corresponding finger portions 11', 12', 13' and 14' thereon. The finger portions 11 to 14 on the palm portion are separated by means of slits 16 which are of lesser depth than the slits 16' between the finger portions 11' to 14' inclusive to correspond to the taper of the crotches between the fingers on a human hand.

The finger portions 12 and 13 on the palm portion 10 are connected to the corresponding finger portions 12' and 13' on the back portion 15 by means of fourchettes 17 of the type shown in Figure 3. The fourchettes 17 are characterized by a straight longitudinal edge 18, inclined end edges 19 and an opposite longitudinal edge 20 which converges from a wide portion adjacent the end edges 19 to a narrower center portion. The fourchettes 17 are provided with oppositely directed tips 21 adjacent the center portion thereof which act as matching points for the corresponding tips 22 on the ends of the finger

portions 12, 12', 13 and 13', thereby facilitating alignment of the fourchettes with the finger portions. The tips 21 and 22 may be gripped with small clamps (not shown), and the fourchette sewed between the finger portions to maintain them in spaced relationship throughout their entire extent, as shown particularly in Figure 7.

The corresponding little finger portions 14, 14' and the adjacent edges 23 and 23' of palm and back portions of the glove are connected by means of a fourchette 24 of the type shown in Figure 4. The fourchette 24 consists of a strip of material having an inclined end 25, a straight edge 26, a short edge portion 27 which converges toward the edge 26 and forms the inner portion of the little finger. The fourchette also includes an outwardly tapering or diverging edge 28 which is adapted to be disposed and connected by stitching from the end of the little finger portions 14, 14' and along the edges 23, 23' of the glove. The fourchette 24 includes matching points 29 which are aligned with the matching points 22 on the little finger portions 14, 14' and additional matching points 30 which are aligned with the matching points 31 and 31' on the palm and back portions of the gloves.

As shown in Figure 1, the back or outer portion of the thumb is formed integrally with the palm portion 10 of the glove. The thumb portion 32 projects at an acute angle to the axes of the finger portions 11 to 14 of the glove from the upper edge of a lateral extension 33 on the palm. The thumb portion 32 has a rounded upper end 34 and slightly diverging lateral edge portions 35 and 35', the latter terminating in a crotch adjacent the base of the forefinger portion 11. The edge 35 of the thumb portion 32 curves outwardly to form a matching point 36 which is adapted to be aligned with a matching point 37 on the back portion 15 of the glove. The palm portion 10 below the thumb portion has a reversely curved edge 38 which is attached by suitable stitching to a curved edge 39 on the back portion of the glove. The thumb portion 32 is of sufficient width to form substantially the entire outer or back portion of the thumb of the glove. The thumb is completed by a fourchette 39 which may, if desired, extend from the upper end 34 of the thumb portion 32 downwardly into the crotch between the thumb and forefinger portions and then upwardly along the forefinger portions 11, 11' of the ends thereof and downwardly into the crotch between the finger portions 11, 11', 12, 12'.

The thumb fourchette 39 is shown in Figure 5. The fourchette 39 consists of a strip of material having a rounded portion 40 and curved converging edges 41 and 42. The edge 41 is formed arcuately and terminates in a point 43 which is sewed in alignment with the matching points 36 and 37 on the palm and back portions of the glove, respectively. The edge 42 of the fourchette 40 merges into a straight edge 44 which converges toward an opposite edge 45 on the fourchette to form a restricted or narrower portion 46 which is disposed adjacent the tip of the forefinger portions 11, 11'. The edge 46' diverges from the narrower portion 46 outwardly from the edge 45. The end 47 of the fourchette is inclined to the edge 45 at an acute angle to conform to the inclination of the crotch between the finger portions 11, 11' and 12, 12'. The fourchette 39 may also be provided with tips or matching points 48 which are aligned with the

tips 22 on finger portions 11, 11' to facilitate attaching of the fourchettes to the gloves.

The fourchette constructions described above are similar to those disclosed in my copending application Serial No. 193,226, now Patent No. 2,125,673, in that the fourchettes are so tapered that the resulting fingers likewise taper from adjacent bases to their tips in the manner that the normal human finger tapers. The tapered fingers thus provide an accurate fit and are devoid of cross seams at the tips of the fingers which would tend to bind and reduce the flexibility and comfort of the glove. If desired, the fourchettes may be made from a plurality of pieces of material.

As shown particularly in Figure 6, the thumb construction formed from the fourchette 39 and the thumb piece 32 is devoid of a seam around the base of the thumb and across the palm portion 10 of the glove. Likewise, the thumb portion 32 is unsymmetrically disposed with respect to the palm and back portions and is so arranged that it projects forwardly from the palm of the glove when in use even as does the normal human thumb. The absence of a seam across the palm of the glove and around the base of the thumb greatly increases the flexibility of the glove and eliminates the seamed protuberance which interferes with the normal action of the hands.

Another form of glove of similar construction is disclosed in Figure 10 and is formed in a like manner from a palm portion 50 and a back portion 51. The finger portions formed on the palm and back portions of the glove are similar to those described above, the main difference residing in the type of thumb portion formed on the glove. In this form of the invention the thumb portion 52 is provided with a rounded end 53 and slightly diverging curved edge portions 54 and 55. The edge portion 54 is formed on a reverse curve and terminates in a matching point 56 which is aligned and attached to a matching point 57 on the back portion 51. The lower portion of the thumb portion 52 has an arcuate edge 58 which terminates within the area of the palm portion 50, thereby forming a slot 59, the edges of which are adapted to be sewed together to provide fullness in the thumb portion of the glove. The arcuate edge portion 58 is sewed to an arcuate edge 60 on the back portion 51, and straight edge portions 61 and 62 are likewise stitched together to connect the palm and back portions.

The fourchette 39 is attached by stitching to the edges of the thumb portion 52 and extends along the forefinger portions 63 and 63' of the palm and back portions of the glove as described above.

In Figure 12 is disclosed a form of glove formed from a single blank of material in which the palm, back and thumb portions are formed integrally, as illustrated in Figure 11. The blank 70 disclosed in Figure 11 consists of an elongated cuff edge 71, curved side edges 72 and 73 which terminate in little finger portions 74 and 74'. A plurality of corresponding finger portions for the middle fingers and forefingers designated generally by the numerals 75 and 75' are also formed in spaced relationship on the blank 70. The thumb portion 76 is disposed between the forefinger portion 75, 75' and is inclined at an angle to the axis of the finger portions. Likewise the finger portion 76 is spaced a greater distance from the forefinger portion 75' than it is from the forefinger portion 75 in order that the thumb portion

76 will be disposed at the edge of the palm of the completed glove and spaced slightly from the back portion of the completed glove. In this type of glove the cuff portion 76' is comparatively full and it does not fit the wrist closely. If it is desired to cause the cuff 76' of the glove to fit the wrist closely, a strap or other similar means 77 may be provided for gathering the glove beneath the thumb portion 76. By gathering the glove in this way, folds are produced adjacent the thumb which allow the thumb to be moved freely and without binding as well as produce a novel and ornamental effect.

If desired, the fullness may be removed from the gloves in the manner illustrated in Figures 13 and 14. In this form of glove the palm portion 80 and back portion 81 are formed integrally and are connected by means of the thumb portion 82. However, a portion of the material is cut out in substantially the form of a V to form a V-shaped notch 83, the edges of which may be stitched together throughout their length to reduce the fullness of the glove. This construction may be further modified by forming the palm and back portions separately with a portion of the thumb piece 82 projecting from each of the palm and back portions. This construction is illustrated in Figure 13, the dotted line 84 extending along the thumb portion being a dividing line upon which the palm and back portions may be separated. In assembling the gloves, they are stitched from the end of the thumb to the lower edges of the palm and back portions.

The form of glove disclosed in Figure 16 is similar to the gloves described above, with the exception that the thumb portion 90 is formed integrally with the back portion blank 91. The palm portion 92 is provided with an inwardly curved edge 93 that is stitched to the substantially complementarily curved outer edge 94 of the lateral extension 95 from which the thumb portion projects. This type of glove is free of seams on the back portion and therefore allows the entire back to be formed from a different type of color of material than the palm portion. The seamless back is also less susceptible to ripping or tearing under stresses, this being important for the reason that greater stresses are exerted on the back of the glove than on the palm, when in use.

Each of the above constructions provides a glove in which a thumb portion is formed integrally with the palm and/or back portions, which therefore provide an extremely attractive appearance and a very flexible and comfortably sitting construction. It will be understood, of course, that the fourchette for completing the thumb portions and the finger portions of these gloves are the same as are illustrated in Figures 3, 4 and 5, or as disclosed in my copending applications Serial No. 193,226 and Serial No. 204,552. It also will be understood that the proportions of the gloves may be varied and the various elements entering into the manufacture of the glove may also be varied in order to produce the desired effect and fit. Therefore the constructions described above should be considered as illustrative only and not as limiting the scope of the following claims.

I claim:

1. In a glove, the combination of palm and back portions having corresponding finger portions projecting therefrom, a thumb portion seamlessly united with at least one of said palm and back portions and adapted to form the entire

back of the thumb of the glove, and a fourchette including a thumb front portion having a rounded end and converging curved edges thereon, said rounded ends and curved converging edges being connected to the end and edges of the thumb portion, respectively.

2. In a glove, the combination of palm and back portions having corresponding finger portions projecting therefrom, a thumb portion having a rounded end and diverging edges seamlessly united with at least one of said palm and back portions, said thumb portion being unsymmetrically disposed with respect to the palm and back portions and adapted to form the entire back of the thumb of the glove, and a fourchette including a thumb front portion having a rounded end and edges converging from said rounded end, attached to the rounded end and diverging edges of said thumb portion to complete the thumb.

20 3. In a glove, the combination of palm and back portions having corresponding finger portions projecting therefrom, a lateral extension seamlessly united with said palm portion having an arcuate convex edge connected to an arcuate concave edge of said back portion, a thumb portion projecting from the upper edge of the lateral extension and forming the major portion of the thumb of the glove, and a fourchette including a thumb front portion connected to the edges of the thumb portion and the edges of adjacent corresponding finger portions on the palm and back portion.

25 4. In a glove, the combination of palm and back portions having side and cuff edges and fingers projecting therefrom, a lateral extension seamlessly united with one of said palm and back portions forming a portion of one of said side edges terminating at said cuff edge, and being connect-

ed to a side edge of the other portion throughout the length of the extension, a thumb back having a rounded end and diverging curved lateral edges seamlessly united with and projecting at an acute angle from the upper edge of said extension and a fourchette including a thumb front portion having a rounded end and converging lateral edges connected to the edges of the thumb back, the adjacent portions of the extension and the edges of the finger portions adjacent to the thumb back.

5 5. In a glove, the combination of palm and back portions having finger portions projecting therefrom and cuff edges, a thumb portion interposed between the palm and back portion and seamlessly united with at least one of said portions, said thumb portion being inclined and unsymmetrical with respect to said palm and back portions and forming the major portion of the thumb, and a fourchette extending along and connecting the edges of the thumb portion to form a thumb disposed at an angle to and merging into the palm portion.

6. The glove set forth in claim 5 in which the thumb portion is seamlessly united with both the palm and back portions.

7. The glove set forth in claim 5, in which the thumb portion comprises two sections seamlessly joined to the palm and back portions and connected by a seam extending from the tip of the thumb portion to the cuff edges of the palm and back portions.

8. The glove set forth in claim 5, in which the thumb portion is seamlessly united with the palm portion and has a lateral edge connected to the back portion by a seam extending to the cuff edge of the back portion.

GLADYS WHITCOMB GEISSMANN.
